INKING MECHANISM FOR PLATE-PRINTING MACHINES.

1,308,114.

Specification of Letters Patent.

Patented July 1, 1919.

Application filed November 10, 1915. Serial No. 60,653.

To all whom it may concern:

Be it known that I, OSCAR ROESEN, a citizen of the United States, residing at New York city, county of Kings, and State of New York, have invented certain new and useful Improvements in Inking Mechanism for Plate-Printing Machines, fully described and represented in the following specification and the accompanying drawings, forming a part of the same.

This invention relates to certain improvements in plate printing machines.

In plate printing machines the printing is done from a flat plate or other surface by means of depressed lines, the surface of the plate being inked and the surplus ink being wiped from that part of the plate in which there are no lines. This removal of the ink is effected by wipers which are usually in the form of rolls of cloth which are gradually renewed by suitable feeding mechanism. In machines of this type the inking mechanism is made wide enough to ink a plate of the maximum size that will be used. In a great many instances, however, plates narrower than the maximum size have to be inked, which causes an unnecessary waste of ink. The ink used in this class of machines is expensive, and, furthermore, the wipers are expensive.

It is the object of the present invention to provide an inking mechanism for this type of machines whereby the ink in the ink fountain may have its position shifted or varied longitudinally of the distributor which distributes the ink from the fountain, so that this distributor may distribute a narrower or wider band or ribbon of ink, depending upon the width of the design on the plate which is to be inked, thus effecting an economy of ink and of the wipers, in that the wipers do not have a surplus of ink to wipe or clean from the plate, where there is no design.

For a full understanding of the invention, reference may be had to the accompanying drawings, in which—

Figure 1 is an end elevation, partly in section, showing the ink fountain and the distributing devices;

Fig. 2 is a side view, partly in section, of a portion of the construction shown in Fig. 1, showing the mechanism for effecting the movement of the ink, and

Fig. 3 is a top view, partly broken away,

of the mechanism for operating the construction shown in Fig. 1.

Referring now to these drawings, the invention is illustrated in connection with a plate printing machine in which the plates are flat plates and are reciprocated beneath the inking mechanism. This inking mechanism in the particular construction includes an ink fountain indicated generally by the numeral 1, open at the bottom, which supplies ink to the distributing mechanism for inking the plate. This distributing mechanism may be widely varied, but in the preferred construction includes a fountain roll 2 and a distributing roll 3 suitably mounted in the frame 4. In the particular distributing mechanism shown, the roll 2 runs under the open end of the fountain, and it and the distributing roll 3 are of sufficient dimensions to ink a design of the maximum width for which the press is adapted.

The construction of the ink fountain 1 may be of any usual type. In the particular construction illustrated it includes a front and rear wall 5, 6, respectively, and ends 7, 80 the ends 7 being united by a top frame 8. As is usual in fountain construction, the front and rear walls beneath which ink is delivered to the distributing mechanism are capable of limited vertical adjustment for delivering variable quantities of ink through the usual adjusting devices 9.

In machines embodying the invention in its preferred form, there will be provided means whereby the ink in the fountain may be so manipulated as to cause the fountain to deliver to the distributor a narrower or wider column of ink as required for the particular design, the rest of the distributor receiving no ink. While these means may be somewhat varied, in the best constructions the fountain will be provided with a pair of movable members which can be moved longitudinally of the cylinder and between which and the front and back walls of the fountain the ink is confined, so that by moving these members the ink will be expanded or contracted, that is, will be so manipulated as to have its position with respect to the roll varied so that a wider or narrower column will be delivered. In the particular construction illustrated these movable members are partitions 10, 11, which extend the width of the fountain, and of sufficient height to confine between them a sufficient quantity of

ink. When the distributer to which ink is delivered is a roll, the lower edges of the partitions will, as shown, be curved to conform to the surface of the roll.

5 These partitions may be supported and given a movement longitudinally of the cylinder in any suitable manner. In the particular construction illustrated, they are provided at their upper ends with threaded 10 extensions 12 into which takes a left and right hand screw 13 mounted in cross arms 14 carried in standards 15 supported on frame 8, before referred to. This screw is manipulated by a hand wheel 16, by the 15 movement of which in one direction or the other the plates can be drawn toward each other or separated, thus either contracting the body of ink and confining its delivery to a narrower surface of the cylinder, or ex- 20 panding it and causing it to deliver to a wider surface. If necessary or desired the bottoms of the plates may be grooved and a suitable packing 17 may be inserted in the grooves contacting with the surface of the 25 cylinder so as to prevent leakage around the lower edges of the plates at the cylinder.

While the invention has been shown and described in its preferred form, it will be understood that various changes may be 30 made in the particular construction for

carrying it out, and that such changes are within the invention.

What is claimed is:

In a plate printing machine, the combination of an ink distributing cylinder, an 35 ink fountain superposed above the cylinder including front and rear walls extending downwardly about the cylinder and having their bottoms shaped to conform to the cylinder curvature, end walls, a top frame 40 uniting the end walls, standards rising from the top frame, cross arms carried by the standards, a right and left hand screw shaft supported in the cross arms, partitions in the fountain above the distributing cylinder 45 and in contact therewith between which the ink is confined supported from the screw shaft, and a hand wheel supported from the screw shaft between the partitions for operating the shaft to move the partitions 50 toward and from each other to vary the width of the ink column delivered to the cylinder.

In testimony whereof, I have hereunto set my hand, in the presence of two subscribing 55 witnesses.

OSCAR ROESEN.
